CARTON

Bruce J. Davidson, Manhasset, N. Y., assignor to
 National Biscuit Company, New York, N. Y., a
 corporation of New Jersey

Application July 31, 1940, Serial No. 348,609

2 Claims. (Cl. 229—35)

My invention pertains to cartons and particularly to cartons having lock-covers. Recently there has been a trend in the packaging art toward the use of Cellophane bags for small articles or articles of light weight such as biscuit, crackers and other dry articles of food. These bags have a decided advantage over paper bags and wrapped packages in that the purchaser can see just the quality and quantity of the articles that he is getting. However, shipment and handling of these Cellophane bags has presented a problem. The filled bags usually have been packed in large cardboard containers that are closed by sealing flaps or by strips of sealing tape, it being necessary to seal the cartons in order to prevent pilferage and to strengthen the container during shipment and storage.

Among the several objects of the present invention are to provide a two piece (top and bottom) carton that is self-locking; that is, a carton in which the act of closing it or placing the cover in closing position automatically locks the cover to the bottom or tray. This not only makes the carton pilfer proof, but also saves the cost of material and labor heretofore required for sealing the cartons. Another object is to provide a carton that is strong and durable and in which the ends and sides will not bulge or bow outwardly. Another object is to provide a lock carton that has smooth ends and sides without external locking flaps or tongues, which in ordinary cartons are so apt to catch and be torn in handling. Another object is to provide a self-sealing or locking carton wherein the lock may be opened or separated without damage to the carton, and the box body or tray may be used as a display for the bags of articles packed therein.

The above and other objects and advantages of my invention are attained by the embodiment thereof illustrated in the accompanying drawings wherein:

Fig. 1 is a blank for forming the bottom or tray of a carton.

Fig. 2 shows the tray formed by folding the blank of Fig. 1.

Fig. 3 is a blank for forming the cover or top of the carton.

Fig. 4 shows the cover formed from the blank of Fig. 3.

Fig. 5 is a section taken on the line 5—5 of Figs. 2 and 4 after the carton has been closed.

Fig. 6 is a section on the line 6—6 of Figs. 2 and 4 showing how the top and bottom of the carton lock together.

Fig. 7 is a blank from which a modified form of bottom or tray may be formed.

Fig. 8 shows the tray formed from the blank of Fig. 7.

Fig. 9 shows a blank for forming a self-locking lid or top that co-operates with the tray of Figs. 7 and 8.

Fig. 10 shows the cover formed from the blank of Fig. 9.

Fig. 11 is a perspective view, partly broken away, showing one end and part of one side of a closed carton formed by placing the cover of Fig. 10 on the bottom of Fig. 8.

Fig. 12 is a section on the line 12—12 of Fig. 11.

Fig. 13 is a section on the line 13—13 of Fig. 11.

Referring first to Figs. 1 to 6, the blank for forming the bottom or tray of the carton is shown in Fig. 1 and is made from a single piece of cardboard which is cut and scored to form a bottom 20, side walls 21, 22 which are joined to the bottom along the score lines 23, 24. Score lines 25, 26 at the ends of the bottom define end flaps 27, 28 which are turned up along the score lines 25, 26 to form the inner face of the end walls. Outer end flaps 29, 30, 31, 32 are connected to the side walls along the score lines 33, 34, 35, 36. When the carton tray is formed as shown in Fig. 3, the flaps 29 and 30 are turned in, outside of the flap 28, and interlocked by the hooks 37, 38 to form one end of the tray. Similarly, at the other end, the flaps 31, 32 are interlocked outside of the end flap 27 to form the other end wall of the tray. The lower edges of the end flaps are cut away or notched out as shown at 41, 42, 43, 44 so that when the flaps are locked together, the ends of the cut-away portions will provide a locking shoulder 45 some distance above the bottom of the tray, as shown in Fig. 2.

The blank of Fig. 3 from which the top or cover of the carton is formed has a top panel 46 to the ends of which the end flaps 47, 48 are connected along score lines 49, 50. Locking lips or tongues 51, 52 are connected to the end flaps 47, 48 along score lines 53, 54.

Sides 55, 56 are connected to the top panel 46 along the score lines 57, 58. Inner end flaps 59, 60, 61, 62 are connected to the ends of the side walls along score lines 63, 64, 65, and 66. The inner end flaps have hooks 67', 68', 69', 70' adapted to interlock when the blank is folded to form the cover. In forming the cover, the sides 55, 56 are first turned up, the flaps 59, 60, 61, 62 turned in and their respective hooks interlocked. The end flaps 47, 48 are next turned up outside of the inner end flaps and the lips

51, 52 turned down inside the cover and over the inner end flaps as clearly shown in Fig. 4. The material from which the cover is made is more or less resilient so that the lips 51, 52 tend to unfold toward each other. The width of the outer ends of the lips as shown in Fig. 3 is substantially equal to, but very slightly less than the width of the locking shoulder 45 shown in Fig. 2. The resilience of the material forces the outer edge of the lips into engagement with the shoulders and automatically locks the cover in place when it is placed over the bottom or tray. This locking is shown in Fig. 6.

It will be noted in Figs. 1 and 3 that the transverse score lines as 33, 26, 34 and 63, 49, 64 are not exactly in alignment, the score lines 26 and 49 being off-set an amount substantially equal to the thickness of the cardboard. When the material is relatively thin the transverse score lines may be in direct alignment.

As shown in Figs. 1 and 2, side walls 21, 22 are provided with slits 67, 68 and the side walls of the cover are notched out to provide tongues 69, 70. When the cover is placed on the tray, the tongues 69, 70 are pressed in against the sides 21, 22 which opens the slits 67, 68 so that the tongues enter them. This prevents the sides of the carton from bulging or bowing out. It will also be noted that the end flaps 47, 48 present a smooth exterior to the ends of the carton so that it will not be caught or torn during shipment or handling.

In practice the tray as shown in Fig. 2, will be filled with merchandise and then the cover of Fig. 4 will be placed over it. The tongues 69, 70 will be pressed in as the cover goes into position, thus entering the slots 67, 68. When the cover is in fully closed position, the lips 51, 52 will spring in under the shoulders 45 which locks the cover to the box. Thus, no tape or glue is necessary for securing the box in closed position. When it is desired to open the box, the purchaser runs a finger under the end flaps 47, 48 which presses the lips 51, 52 outward away from engagement with the shoulders 45 so that the cover can be lifted off. When the material packed in the carton is "Cellophane" bags filled with merchandise, the tray may be used as a means for effectually displaying them.

Reference will now be had to Figs. 7 to 13 wherein I have illustrated another embodiment of my invention. The blank for forming the bottom or tray is shown in Fig. 7 and comprises a bottom 71 to the ends of which end flaps 72, 73 are joined along the usual score lines and sides 74, 75 are joined along similar score lines. Outer end flaps 76, 77, 78, 79 likewise are joined to the ends of the sides along score lines. Each of the inner end flaps is provided with a slit 80, 81 and each of the outer end flaps is provided with a hook 82, 83, 84, 85 which are adapted to interlock with the inner end flap through the slits 80, 81. The outer end flaps are cut away in part along one edge and the hooks cut along straight lines as shown at 86, 87, 88, 89 so that when the bottom tray is formed as shown in Fig. 8 a locking shoulder 90 will be provided at each end. Each side wall is provided with a longitudinal slit 91, 92 to receive a tongue formed on the cover similar to the function of the slits 67, 68.

The blank for forming the cover is shown in Fig. 9 and comprises a top panel 93 to which the end walls 94, 95 are joined along the usual score lines, the end walls at their outer edges being provided with lips or tongues 96, 97, the side edges

of which are provided with hooks 98, 99 and 100, 101. The length of these lips from the extremities of the hooks (as from 98 to 99) is substantially equal to, but may be very slightly less than the length of the shoulder 90.

Side walls 102, 103 are attached to the top panel along the usual score lines and are provided with tongues 104, 105 which are adapted to enter the slits 91, 92 when the carton is closed as shown in Figs. 11 and 13.

To form the tray as shown in Fig. 8, the inner end flaps 72, 73 are first turned up to vertical position, then the side walls 74, 75 are turned up and the flaps 76, 77 and 78, 79 turned in outside of the flaps 72, 73 and the hooks interlocked with the inner end flaps through the slits 80, 81.

The side and end walls of the blank of Fig. 9 are turned up as shown in Fig. 10 to form the cover. When the cover is inserted over the bottom or tray shown in Fig. 8, the tongues 104, 105 are guided into the slits 91, 92 and the lips 96, 97 are pressed in above the slits 80, 81 so that they enter into the slits and the hooks 98, 99 and 100, 101 engage against the abutments 90 and also against the material of the inner end flaps above the slits 80, 81 which automatically locks the cover in closed position.

It will thus be seen that I have provided a carton which automatically locks itself when closed and does not require to be sealed with tape or glue, thus effecting a considerable economy in both material and labor. Also the carton has a relatively smooth exterior with few or no projecting flaps or tongues to be caught and torn. The carton cannot be easily opened or its contents tampered with.

While I have illustrated two forms of my invention, it may be embodied in many other modifications and I claim all such that come within the scope of my claims.

What I claim is:

1. A lock carton comprising a bottom tray and a cover, the tray having bottom, side and end walls, each end wall being formed from an end flap connected along its lower edge to the bottom and two side flaps disposed outside the end flap and connected at one end to the ends of opposite side walls, the other ends of the side flaps overlapping and interlocking, the side flaps having upper and lower edges and being cut away in part on their lower edges including the overlapping portions so as to provide a locking shoulder parallel to the top of the tray and spaced from the bottom, said cover having top, side and end walls, said side and end walls fitting over and outside of the side and end walls of the tray, said cover end walls having straight edged lips extending inwardly and upwardly from their lower edges, the straight edges of the lips engaging the locking shoulders provided by the cut-out portions of said interlocking side flaps to lock the cover to the tray.

2. A lock carton comprising a bottom tray and a cover, the tray having bottom, side and end walls, each end wall being formed from an end flap connected along its lower edge to the bottom and two side flaps disposed outside the end flap and connected at one end to the ends of opposite side walls, the other ends of the side flaps overlapping and interlocking, the side flaps having upper and lower edges and being cut away in part on their lower edges including the overlapping portions so as to provide a locking shoulder parallel to the top of the tray and spaced from

the bottom, said cover having top, side and end walls, said side and end walls fitting over and outside of the side and end walls of the tray, said cover end walls having straight edged lips extending inwardly and upwardly from their lower edges, the straight edges of the lips engaging the locking shoulders provided by the cut-out por-

5 tions of said interlocking side flaps to lock the cover to the tray, each of the tray side walls having a slot spaced from its four edges and each of the cover side walls having a tongue that engages within the respective tray side slots to prevent outward bowing of the cover side walls.

BRUCE J. DAVIDSON.
